DESIGN FOR A PAIR OF SCISSORS

Kurt Schlesinger, New York, N. Y.

Application December 11, 1943, Serial No. 111,987

Term of patent 14 years

To all whom it may concern:

Be it known that I, Kurt Schlesinger, a citizen of no country (having received first U. S. papers for citizenship), and residing in the city, county, and State of New York, have invented a new, original, and ornamental Design for a Pair of Scissors, of which the following is a specification, reference being made to the accompanying drawing, forming a part thereof.

Fig. 1 is a top plan view of a pair of scissors showing my new design.

Fig. 2 is a side-elevational view of the pair of scissors of Fig. 1.

Fig. 3 is a bottom plan view of Fig. 2.

I claim:

The ornamental design for a pair of scissors, substantially as shown.

KURT SCHLESINGER.
